United States Patent Office

Des. 198,595
Patented July 7, 1964

198,595

BOX

Jerome Shiffman, 128 Cartage Road, Scarsdale, N.Y.

Filed June 22, 1962, Ser. No. 70,651

Term of patent 7 years

(Cl. D58—12.7)

FIG. 1

FIG. 2

FIG. 3

FIG. 4

FIG. 5

FIG. 1 is a front elevational view of a box showing my new design;

FIG. 2 is a side elevational view thereof, the opposite side being a mirror image thereof;

FIG. 3 is a top plan view thereof;

FIG. 4 is a rear elevational view thereof; and

FIG. 5 is an isometric view thereof, the box being partially open.

I claim:

The ornamental design for a box, as shown and described.
